UNITED STATES PATENT OFFICE

ROBERT BLUME, OF HOOD, CALIFORNIA

RAIL CHAIR

Application filed July 7, 1930. Serial No. 465,984.

The invention is a rail chair.

The object of the invention is to provide a rail chair which is a combination tie plate and rail brace of unitary construction which will positively position itself in a tie and absorb the lateral thrust of the rails, especially on curves.

Another object of the invention is to provide a rail chair as outlined which will be light in weight, positively retained in position on a tie, readily removed and replaced, and which will permit a certain flexibility in the rail, and being so formed adjacent the spike holes as to permit convenient manipulation of a spike puller for withdrawing the spikes.

The invention consists primarily of a tie plate having an integral rail brace extending throughout its length and fitting closely to the flange and flange fillet and having a slight clearance at the upper portion of the web and web-ball fillet and the ball, the brace clearing the greater portion of the web, and provided with a core extending longitudinally therethrough, the outer wall being inclined at an angle of substantially forty five degrees, and the tie plate having integral ribs on the bottom face diagonally and longitudinally disposed, the inner side of the tie plate upper surface continuing as a flat base to a point approximating the outer edge of the spike holes, thence extending upwardly to coincidence with a plane tangential to the inclined upper surface of the rail flange, and continuing outwardly at similar inclination to the edge of the plate, spike holes being placed out of transverse alignment.

Referring to the accompanying drawings:

Fig. 1 is a top plan view of the invention; Fig. 2 is a bottom plan view showing the embedding ribs;

Fig. 3 is a transverse section taken on line 3-3 of Fig. 2 and indicating a rail and spikes in position.

Similar reference characters are used to designate similar parts throughout the several views.

The tie plate 4 is provided on its undersurface with diagonal embedding ribs 5 and longitudinal ribs 6 which are adapted to embed

in the tie due to the weight of the rolling stock, thereby keying the plate to the tie. A plurality of spike holes 7 and 8 are out of transverse alignment to prevent splitting of the ties by the spikes.

The upper surface of the tie plate is provided with a flat flange receiving portion 9 extending outwardly to adjacent the outer edge of the spike holes 8, thence having a vertical shoulder 10 terminating at coincidence with an extension of the inclined surface 11 of a rail flange, then extending to the edge of the plate with the same inclination as at 12 thus providing a shoulder for the back surface of the spike 13 adjacent the head.

The rail brace 14 is cast or formed integral with the tie plate and forms an angular recess with the tie plate as at 15 for cooperation with the flange of the rail and continuing into a shoulder 16 cooperating with the lower portion of the rail web thence continuing with a portion 17 clearing the web, the upper portion 18 slightly clearing the upper portion of the web and lower face of the ball of the rail, the outer wall 19 being inclined at an angle of approximately forty five degrees terminating in the tie plate. The brace 14 is cored throughout its length, as at 20, for the purpose of reducing weight and economizing on material.

Installation of the device is accomplished by passing the tie plate under the rail and on top of the tie, and driving the spikes 13 which by cooperation with the shoulder 10 lock the rail in position. A slight transverse flexure of the rail is necessary to form contact at the shoulder 18 before the brace 14 is brought into action, and the embedding of the ribs 5 and 6 in the tie effectively retain the plates and coincidentally the rail in their relative positions.

I am aware that rail chairs, tie plates and rail braces have been made, therefore I do not claim such devices broadly but I do claim:

1. A rail chair comprising a tie plate and rail brace of unitary construction, said rail brace being adapted to engage the lower portion of the web of a rail and to slightly clear

the upper portion of the web and undersurface of the ball of a rail.

2. A rail chair comprising a tie plate and rail brace of unitary construction, said rail brace being formed so as to engage the upper surface of a rail flange and the lower portion of the rail web, the upper portion of said brace slightly clearing the upper portion of the rail web and undersurface of the rail ball, said rail brace extending throughout the length of said tie plate.

3. A rail chair comprising a tie plate and rail brace of unitary construction, said rail brace being formed so as to engage a rail flange and the lower portion of the rail web, the upper portion of said brace slightly clearing the upper portion of the rail web and the undersurface of the ball of the rail, said rail brace extending diagonally downward from the ball portion to the tie plate.

4. A rail chair comprising a tie plate and a rail brace of unitary construction and of equal length and formed so as to engage the flange of a rail and the lower portion of the web thereof, and a ball engaging portion normally slightly clearing the upper portion of the web and undersurface of the ball of a rail, continuing therefrom diagonally downward to said tie plate, the body of said brace having a substantially triangular aperture formed longitudinally therethrough.

5. A rail chair comprising a tie plate and a rail brace of unitary construction and of equal length and formed so as to engage the flange and lower web portion of a rail, the upper section of said brace being normally out of contact with the upper portion of the web and undersurface of the ball of said rail, continuing therefrom diagonally downward at an angle of approximately forty-five degrees to said tie plate, the body portion of said brace having a triangular lightening hole cored therethrough longitudinally, said tie plate having a plurality of projecting ribs on the undersurface adapted to embed in a tie.

6. A rail chair comprising a tie plate and rail brace of unitary structure and of substantially equal length, formed to engagingly receive the flange of a rail and to slightly clear the upper portion of the web and undersurface of the ball of the rail, the outer surface of said brace having an inclination of approximately forty five degrees, a triangular lightening core hole formed longitudinally through the body portion of said brace, diagonal and longitudinal embedding beads on the undersurface of said tie plate, a plurality of spike receiving apertures in longitudinal but not transverse alignment, a shoulder extending throughout the length of said tie plate coinciding with the outer edge of the spike receiving apertures, and in a continuation of the plane of the upper surface of the rail flange, continuing to the edge

of the plate in a prolongation of the inclined surface of said rail flange.

In testimony whereof I have affixed my signature.
